Safe Filler

H. H. Bryant,

Filling for Fire-Proof Safes.

Patent No. 67,629.

Patented Aug. 13, 1867.

United States Patent Office.

HEZEKIAH H. BRYANT, OF BOSTON, MASSACHUSETTS.

Letters Patent No. 67,629, dated August 13, 1867.

IMPROVEMENT IN FILLING FOR SAFES.

The Schedule referred to in these Letters Patent and making part of the same.

TO ALL WHOM IT MAY CONCERN:

Be it known that I, HEZEKIAH H. BRYANT, of the city of Boston, county of Suffolk, and State of Massachusetts, have invented a new and improved Filling for Fire or Burglar-Proof Safes; and I do hereby declare the following to be a full and correct description of the same, reference being had to the accompanying drawing, and the letters of reference marked thereon, making a part of this specification.

The accompanying drawing represents a vertical section of a safe commonly termed "steam fire-proof," which is used to illustrate my invention, as safes of this kind are the most open to a successful attack by burglars.

In the drawing shown, A represents the exterior surface of such a safe, B its air or steam-chamber, C its water-chambers or vessels, D the vents connecting said water-vessels or chambers with said air or steam-chamber.

It is well known that the mode of attack upon a safe usually adopted by burglars is that of drilling or boring holes in chambers therein, which are charged with powder or other explosive material, which, when exploded, serves to make an opening in the structure suitable for their purposes, so that safes provided with steel chests or vaults are not proof against such attacks, as that part of the structure is both small and light enough to permit of its being easily carried away and opened at leisure so soon as it is freed from the case enclosing it, which is accomplished by the means just mentioned.

My invention consists of the use of sponge, or any other article of a similar porous and absorbent nature, in combination with any liquid placed in the chambers between the several walls of a safe, the which effectually prevents said chambers from being emptied of the liquid contained therein by means of boring or drilling into said chambers, as the sponge will retain enough thereof to dampen and thereby destroy any charge of powder or other similar material that may be introduced therein.

In that kind of a safe shown in the accompanying drawing, I introduce into the steam or air-chamber a sufficient amount of sponge to entirely fill the same, as its porous nature easily admits of the free passage or circulation of steam; and in the water-chamber of vessels I place enough sponge to insure the retention of enough of the water or other liquid to dampen whatever charge of powder or like material that may be introduced therein.

I have lately invented a steam-safe, for which I have applied for Letters Patent. In the water-chambers provided by my mode of manufacture it would be practicable to place enough sponge to entirely fill the same, if a tube reaching from the common centre of each water-chamber to any point without the same were used instead of my flexible tube and buoy. With them the sponge would have to be placed about the sides of the water-chambers, so as to permit the operation of the said tube and buoy for conducting off any steam or vapor that might be generated in said chambers, as would the tube first instanced.

Having thus fully described my invention, I wish it to be clearly and fully understood that I do not confine the use or application of my invention to steam-safes, or those of any particular make, nor do I confine myself to the use of sponge, for any other article of a similar nature may be used with advantage. What I do claim, and desire to secure by Letters Patent, is—

The use of sponge as a filling for a safe or other structure of a similar nature, or any other porous and absorbent substance that is its substantial equivalent, as and for the purpose herein set forth.

The above specification of my said invention signed and witnessed at Boston this twenty-first (21st) day of June, A. D. eighteen hundred and sixty-seven (1867).

H. H. BRYANT.
